UNITED STATES PATENT OFFICE.

CHARLES D. HASKINS, OF NEW YORK, N. Y., ASSIGNOR, BY MESNE ASSIGNMENTS, TO THE WESTERN ELECTRIC COMPANY, OF CHICAGO, ILLINOIS.

TELEPHONE CIRCUIT-CHANGER.

SPECIFICATION forming part of Letters Patent No. 293,171, dated February 5, 1884.

Application filed February 9, 1881. (No model.)

To all whom it may concern:

Be it known that I, CHARLES D. HASKINS, a citizen of the United States, residing at the city of New York, in the county of New York 5 and State of New York, have invented certain new and useful Improvements in Telephone Circuit-Changers, of which the following is a full, clear, concise, and exact description, reference being had to the accompanying drawings, forming a part of this specification.

My invention is designed to facilitate the work of switching at the central office of a telephone-exchange, and is an improvement upon the jackknife - switch heretofore used 15 upon the general switch-board. Each subscriber is connected by an independent telephone-line with a switch upon the general switch-board, which passes from said switch through an annunciator and thence to ground. 20 The final connection between any two telephone-lines is made by a flexible conducting-cord connected from one of the switches to the other. A complete metallic circuit has been used for each terminal station, in which case 25 the circuit, instead of passing to ground, as before described, would pass back to the terminal station through the annunciator and another switch, which should be placed upon the switch-board near the first switch of said 30 circuit. Instead of two switches for each complete metallic circuit, a single double switch, as hereinafter shown, may be used. My switch may also be used where a part of the telephone-lines are open at the central office.

35 In the drawings, Figure 1, Sheet 1, shows a front elevation of a switch embodying my improvements. Fig. 2 is a section thereof upon line $x-x$ of Fig. 1. Fig. 3, Sheet 2, shows a switch-board with modifications of my switch. 40 Fig. 4 is a section of Fig. 3 upon line $y-y$. Fig. 5 shows an end of a single flexible conducting-cord provided with a metallic tip. Fig. 6 shows an end of a double flexible conducting-cord provided with metallic tips, each 45 connected with a single strand of the cord, and Fig. 7 shows a single and double line connected.

The central office may be notified in any of the well-known ways what connection is desired. For example, an electric current may 50

be sent along the telephone-line a , which finds circuits through the switch as follows: by bolt b to plate c ; thence to lever or key d , which is held in contact with insulated contact stop or point e by spiral spring f . Line g 55 is connected from point e through an annunciator, and thence by wire h to ground. When the switch is connected with the operator's telephone, or with the switch of another telephone-line, by placing the eyelet of the tip of 60 the single conducting-cord upon the hook i , as indicated by dotted lines, the position of the lever is changed and its contact with point e broken. In Fig. 4, Sheet 2, the telephone-line l connects with bolt m , which connects 65 with spring or key n , which is in contact with contact stop or point o . Line p is connected from point o through an annunciator, and thence by wire q to ground. When the eyelet 70 of a cord-tip is placed upon the hook r , the contact between n and point o is broken and a new contact formed between the spring and the metallic tip of the cord. The double switch shown in Fig. 3 consists of springs s and s' and stops t and t' . The complete metallic circuit is, as indicated, from the terminal station of a subscriber to spring s , which is in contact with stop t , and from stop t , after passing through an annunciator, to stop t' , and from spring s' back to the terminal station. 75 By means of a flexible double conducting-cord provided with suitable tips, the metallic circuits of two such switches may be formed into one metallic circuit passing from one terminal station through the central office to the other 80 terminal station, and thence back through the central office to the first terminal station. When the eyelet u of the rubber block of the tip (see Fig. 6) is forced upon the hook of a double switch, the two springs of the switch 85 are sprung back from contact with their respective stops, and the metallic points v v' are brought into contact with the springs. When it is desired to connect a double switch with a single switch, the tip at one end of the double 90 conducting-cord should be like the one shown in Fig. 6, while each of the other ends of the strands, or at least one of them, should be provided with a tip like the one shown in Fig. 5. 95 The double-pointed tip is placed upon the 100

hook of the double switch, as before described, and one of the strands of the cord connected by means of its single tip with the single switch, while the other strand is connected to ground. Thus the circuit of the two terminal stations is as follows: from the ground of the first terminal station to the spring of the single switch, and thence through one strand of the cord to one spring of the double switch; 5 thence through the outfit at the second terminal station and back to the other spring of said double switch, and from last-mentioned spring through the other strand of the double conducting-cord to ground.

15 In Sheet 3, Fig. 7, I have shown two subscribers' stations, A and B, thus connected together through the central office, C, by means of my switching apparatus. The telephone-line *l* of station A is connected to spring *n* of the single switch at the central office, and thence, as shown, through one strand of the cord to spring *s* of the double switch, and thence through the outfit at station B and back to the other spring, *s'*, of the double 20 switch, and thence to ground at the central 25

office through the other strand of the cord, as shown.

I claim as my invention and desire to secure by Letters Patent—

1. The combination of spring *n*, stop *o*, and hook *r*, or their equivalents, with a flexible 30 conducting-cord, substantially as and for the purpose specified.

2. The tip of a double conducting-cord, consisting of a rubber block provided with eyelet *u* and contact-points *v* and *v'*, each connecting with a strand of the cord, substantially as and for the purpose specified. 35

3. The combination, at the central office of a telephone-exchange, of the single switch and the double switch, and means, as described, whereby the single telephone-line of station A and the metallic circuit of station B may be united to form a single ground-circuit, substantially as and for the purpose specified. 40

CHAS. D. HASKINS.
